United States Patent Office

Des. 208,691
Patented Sept. 26, 1967

208,691

PULL

John R. Morgan, Wheeling, Ill., assignor to Amerock Corporation, Rockford, Ill., a corporation of Connecticut

Filed Jan. 30, 1967, Ser. No. 5,603

Term of patent 14 years

(Cl. D10—8)

FIGURE 1 is a top view of the pull incorporating my new design.

FIG. 2 is a front view of a pull.

FIG. 3 is an enlarged side view as seen from the left in FIG. 1.

FIG. 4 is an enlarged sectional view taken along the line 4—4 in FIG. 2.

FIG. 5 is an enlarged sectional view taken along the line 5—5 in FIG. 1.

FIG. 6 is a sectional view taken along the line 6—6 in FIG. 2.

I claim:

The ornamental design for a pull, as shown.
